US00D793017S

(12) **United States Design Patent** (10) **Patent No.:** **US D793,017 S**
Woods (45) **Date of Patent:** **** Jul. 25, 2017**

(54) **GRILL CLEANING DEVICE**

(71) Applicant: **Grillbot, LLC**, New York, NY (US)

(72) Inventor: **Ethan Woods**, New York, NY (US)

(73) Assignee: **Grillbot, LLC**, New York, NY (US)

(**) Term: **15 Years**

(21) Appl. No.: **29/552,690**

(22) Filed: **Jan. 25, 2016**

Related U.S. Application Data

(60) Division of application No. 29/482,173, filed on Feb. 14, 2014, now Pat. No. Des. 753,355, which is a continuation-in-part of application No. 29/451,847, filed on Apr. 9, 2013, now abandoned, said application No. 29/552,690 is a continuation-in-part of application No. 14/884,675, filed on Oct. 15, 2015, now Pat. No. 9,408,458, which is a continuation of application No. 13/671,125, filed on Nov. 7, 2012, now Pat. No. 9,161,612.

(57) **CLAIM**

The ornamental design for a grill cleaning device, as shown and described.

DESCRIPTION

FIG. 1 is a perspective view of a grill cleaning device, showing my new design;

FIG. 2 is a front view of the grill cleaning device shown in FIG. 1;

FIG. 3 is a rear view of the grill cleaning device shown in FIG. 1;

FIG. 4 is a left side view of the grill cleaning device shown in FIG. 1;

FIG. 5 is a right side view of the grill cleaning device shown in FIG. 1; and,

FIG. 6 is a top view of the grill cleaning device shown in FIG. 1.

The broken lines are included for the purpose of illustrating environmental and unclaimed portions of the grill cleaning device and form no part of the claimed design.

1 Claim, 4 Drawing Sheets
